DESIGN FOR A CARPET SWEEPER

Findley Williams, Park Ridge, Ill., assignor to Bissell Carpet Sweeper Co., Grand Rapids, Mich.

Application April 15, 1937, Serial No. 68,793

Term of patent 14 years

To all whom it may concern:

Be it known that I, Findley Williams, a citizen of the United States, residing at Park Ridge, in the county of Cook and State of Illinois, have invented a new, original, and ornamental Design for a Carpet Sweeper, of which the following is a specification, reference being had to the accompanying drawing, forming part thereof, in which:

Fig. 1 is a top plan view of the carpet sweeper.
Fig. 2 is a front elevational view taken from the bottom of Fig. 1, the bail element shown in Figs. 1 and 3 being omitted for convenience of illustration.

Fig. 3 is an end elevational view of the carpet sweeper taken from the right end of Fig. 1 and on an enlarged scale in relation to Figs. 1 and 2.

I claim:

The ornamental design for a carpet sweeper, as shown and described.

FINDLEY WILLIAMS.
